CHARLES F. REBTOY Inventor

By Herman A. Philipp

Attorney

UNITED STATES PATENT OFFICE.

CHARLES F. REBTOY, OF FLINT, MICHIGAN.

RAILWAY-SWITCH.

1,144,247.

Specification of Letters Patent. Patented June 22, 1915.

Application filed March 3, 1915. Serial No. 11,751.

To all whom it may concern:

Be it known that I, CHARLES F. REBTOY, a citizen of the United States of America, residing at Flint, in the county of Genesee and State of Michigan, have invented certain new and useful Improvements in Railway-Switches, of which the following is a specification.

The present invention relates to improvements in railway switches, and is designed especially to provide a compact mechanism especially adapted for automatically operating street railway switches.

The primary object of the invention is the provision of mechanism adapted to operate a switch, but which mechanism is actuated from a tappet or contact member carried by the railway car.

The invention consists in certain novel combinations and arrangements of parts of the operating mechanism as will be fully pointed out hereinafter and claimed.

In the accompanying drawings I have illustrated one complete example of the physical embodiment of my invention constructed according to the best mode I have so far devised for the practical application of the principles of the invention.

Figure 1 is a plan view showing a box or casting with the lid removed, and the operating mechanism of the device disclosed therein. Fig. 2 is a transverse sectional view showing the box top and a wear plate thereon, and showing the slot construction of the wear plate and box top. Fig. 3 is a longitudinal vertical sectional view of the box, taken at two different planes, for convenience of illustration. Fig. 4 is a view showing the actuating mechanism of the device carried by the railway car.

In the preferred embodiment of the invention as illustrated in the drawing, I employ a metallic casting or box 1, which is preferably open at the upper end and provided with a top or cover 2, which is screwed or otherwise secured to the box 1. The box is provided with perforated lugs or flanges 3—3, by means of which it is secured to a suitable member inside the conduit or pit beneath the railway road bed. The box is designed to be bolted to the stationary member aforementioned, and stands with its operating parts in the position shown in Fig. 3.

Near the closed bottom end 4 of the box a transverse shaft 5 is located which ex-

tends between two perforated lugs or bosses 6—6, each of which is integral with a side of the box 1, and this shaft 5 is supported in these two bosses 6—6. The shaft is placed in position through either of the two openings 7—7 in the sides of the box 1, and these openings, after the shaft is in position, are closed by a pair of plugs 8.

The shaft 5 is designed to support a rocking plate which comprises the sleeve 9 extending across the box, and a cam member or abutment 10 integral therewith. This abutment member is a plate having a shoulder 11 formed at its upper edge, and in Fig. 3 extensions 12 and 13 are provided which are adapted to coact with the lugs 14 and 15 respectively. These lugs 14 and 15 are cast integral with, and project inwardly from, one of the side walls of the box, and are in the path of movement of the rocking plate. As seen in Fig. 3, the extension 12 of the rocking plate is in position over the lug 14, and it will be noted that the lugs 14 and 15 are situated at an angle so these extensions may rest squarely upon the lugs.

The normal position of the rocking plate is shown in the drawings, with the shoulder 11 in upright position, and the rocking plate is held in this position by means of a pair of coil springs 16 and 17 that are attached at 18 to an end wall of the box, and their other ends are attached to the arms 19—19 which project upwardly from the sleeve 9. These two springs hold the rocking plate in upright position as shown in Fig. 3.

The end of the rocking sleeve 9 opposite the rocking plate 10, is fashioned with an operating arm 20 which projects upwardly from the sleeve and has pivoted at its free end a horizontally arranged plunger bar 21. The bar 21 is connected to arm 20 by a link 20' having the pivots 22 and 22'. The plunger bar is supported in and is free to move through a pair of bearing sockets 23—23, and these socket members 23—23 are each secured to the side wall of the box 1 by means of a screw as 24.

A link 25 pivoted at 26 to the under side of the plunger bar 21 is pivoted at 27 to the arm 28 of the bell crank lever 29, which is pivoted on a post 30 that rises vertically from the bottom of the box 1. The other arm 31 of the bell crank lever is connected by a link 32 pivoted thereto at 33 to a push bolt 34, the connection with the push bolt

being made by the pivot 35. This push bolt, as clearly seen in Fig. 1, is adapted to move in a direction at right angles to the plunger bar, and is supported in a perforated boss 36, a packing nut 37 being threaded into the boss to support the push rod therein. The push rod has its end 38 projecting normally through a perforation 39 in one side of the box, and is adapted to move the switch tongue 40, indicated in dotted lines, Fig. 1.

The rocking plate 10, as clearly seen in Fig. 3, projects upwardly through a slot 41 in the top 2 of the box, and also through a slot 42 in a wear plate 43 which is fixed on top of the lid or top 2 of the box. A groove 44 extends approximately the length of the wear plate, and has a curved end wall 45. At each side of the groove 44 and slot 42 I locate a felt strip 46. Between these two strips the rocking plate 10 is designed to swing and be guided.

The above described mechanism is the operating device for the railway switch tongue 40, and this device is actuated by the mechanism illustrated in Fig. 4. This mechanism is carried on the car and comprises a socket member 46 secured in the floor of the car and having a spring pressed foot trip 47. This trip is designed to pull a cable 48 passing over the pulley 49, and the cable has its other end attached to a bell crank lever 50 pivoted at 51 in a bracket 52, carried under the car, and in position where the tappet member 53 may pass through the groove 44 in the wear plate. This tappet member is spring pressed, and is integral with the plunger 54, which is connected by pivoted link 55 with the bell crank 50, and a spring 56 holds the parts in position so that the tappet 53 is out of operative position. When it is desired to move the tappet to operative position, pressure on the foot trip 47 will pull the cable 48 and move the bell crank 50, so that the tappet 53 is projected to proper position to travel through the slot 44 in the wear plate 43. It will be readily seen by referring to Fig. 3, that when the tappet 53 enters the groove 44 at the left, it will travel to the right and encounter the shoulder 11 on the rock plate 10. The contact of the tappet with the shoulder, and the continued movement of the tappet causes the plate 10 to rock on the shaft 5, and as the arm 20 also rocks, it will shove the plunger bar 21 to the right. This movement will cause the bell crank 29 to swing on its pivot 57, and the movement of the plunger bar will be transferred to the push bar. In this manner the push bar is shoved through the boss or bracket 36, and its end 38 being in contact with the switch tongue 40 will swing the tongue on its pivot as readily understood.

The passage of the tappet 53 rides down the rock plate 10 until the plate encounters the lug 15, and by this time the tappet is freed from the shoulder of the plate. The two springs 16 and 17 now retract the rocking plate 10 to normal position, and the extension 12 rests upon the lug 14.

It will of course be understood that this device is applicable for use on a railway track when the car is passing to the right in the figures of drawing, but the device can equally well be applied for use on the railway track going in the opposite direction for the purpose of throwing the switch.

From the above description taken in connection with my drawings it is evident that I have produced an economical, and efficient device, which is compactly arranged within the pit of the switch mechanism, and which is extremely simple in its construction and operation.

What I claim is:

1. The combination with a box and a shaft therein, of a sleeve on said shaft, an arm on the sleeve in position to be moved by a tappet on a passing car, a rocker arm on said sleeve, a plunger bar pivoted to said rocker arm, a push bar at right angles to said plunger bar adapted to engage a switch tongue, and connections whereby the movement of the plunger bar is transmitted to the push bar.

2. The combination with a box having a slotted top and a wear plate thereon provided with a groove, of a rock sleeve supported in the box and a plate and rocker arm at opposite ends of said sleeve, said plate projecting through said slots and groove, and means for limiting the movement of said plate, a push bar adapted to engage a switch tongue, and connections between said rocker arm and push bar for actuating the bar.

3. The combination with a box having a slotted lid and a slotted wear plate provided with a groove, of a rock sleeve supported in the box having a plate formed with extensions, and a central shoulder, lugs on the box in the path of movement of said extensions, and springs for holding the plate in normal position, a rocker arm at the opposite end of the rock sleeve, a plunger bar pivoted to said rocker arm, a push bar movable at right angles to said plunger bar, a bell crank lever, and links connecting the respective ends of said lever to the plunger bar and push bar.

In testimony whereof I affix my signature in presence of two witnesses.

CHARLES F. REBTOY.
